UNITED STATES PATENT OFFICE.

WILLIAM H. TOWNSEND, OF PHILADELPHIA, PENNSYLVANIA, ASSIGNOR OF
TWO-THIRDS TO SAMUEL T. MACHETTE AND JOSEPHINE M. MEIERE, OF
SAME PLACE.

SOAP.

SPECIFICATION forming part of Letters Patent No. 281,807, dated July 24, 1883.

Application filed May 31, 1883. (No specimens.)

To all whom it may concern:

Be it known that I, WILLIAM H. TOWNSEND, a citizen of the United States, residing in the city and county of Philadelphia, State of Pennsylvania, have invented a new and useful Improvement in Soap, which improvement is fully set forth in the following specification.

In carrying out my invention I take one hundred-weight of oleine soap, two pounds of ammonia, one and a half pound glycerine, four ounces of laudanum, and thirteen pounds pulverized pumice-stone. The proportions may, however, be varied.

The oleine soap, which should be pure, is rendered, and, while the same is boiling, the ammonia, glycerine, and laudanum, well mixed together, are united to it. The pumice-stone

is next added, and the whole mass thoroughly worked and incorporated while cooling.

Any essential oil as perfume may be added 20 at the proper time.

The soap will be found to possess deterutive and emollient qualities of superior nature, the ammonia being preserved throughout.

Having thus described my invention, what I 25 claim as new, and desire to secure by Letters Patent, is—

A soap composed of the ingredients set forth—viz., oleine soap, ammonia, glycerine, laudanum, and pulverized pumice-stone.

WM. H. TOWNSEND.
